UNITED STATES PATENT OFFICE

EDGAR W. OZMON, OF MINNEAPOLIS, MINNESOTA

DESIGN FOR A DEVICE TO BE WORN ON NECKTIE OR CLOTHING

Application filed December 5, 1931. Serial 41,975. Term of patent 14 years.

To all whom it may concern:

Be it known that I, EDGAR W. OZMON, a citizen of the United States, residing at Minneapolis, in the county of Hennepin and State of Minnesota, have invented a new, original, and ornamental Design for a Device to be Worn on Necktie or Clothing, of which the following is a specification, reference being had to the accompanying drawings forming part thereof.

Fig. 1 is a view in front elevation of the device;

Fig. 2 is a view in side elevation of the device;

Fig. 3 is a view in rear elevation of the device;

Fig. 4 is a vertical section on line 4—4 of Fig. 3, as indicated by the arrows; and

Fig. 5 is a horizontal section taken on line 5—5 of Fig. 1 as indicated by the arrows.

I claim:

The ornamental design for a device to be worn on necktie or clothing, as shown.

EDGAR W. OZMON.
